UNITED STATES PATENT OFFICE.

WILLIAM R. VERSTRAELEN AND CHRISTIAN ALTER, OF NEW YORK, N. Y.

PICKING DEVICE FOR ZITHERS.

SPECIFICATION forming part of Letters Patent No. 769,518, dated September 6, 1904.

Original application filed September 3, 1903, Serial No. 171,752. Divided and this application filed April 20, 1904. Serial No. 204,307. (No model.)

To all whom it may concern:

Be it known that we, WILLIAM R. VERSTRAELEN and CHRISTIAN ALTER, both citizens of the United States, and residents of the city of New York, borough of Manhattan, in the county and State of New York, have invented new and useful Improvements in Picking Devices for Zithers, of which the following is a full, clear, and exact description, this being a division of the application for Letters Patent of the United States for a self-playing zither, Serial No. 171,752, filed by us September 3, 1903.

The object of the invention is to provide a new and improved picking device for self-playing zithers arranged to insure a proper automatic picking of the strings according to the notation of a note-sheet.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional plan view of the improvement. Fig. 2 is a like view of the same with the parts in a different position. Fig. 3 is a front elevation of the same. Fig. 4 is an enlarged sectional front elevation of the pickers and the levers for imparting a swinging motion to the same, and Fig. 5 is a side elevation of part of one of the bass-strings of the zither.

On a suitably-constructed stand or support A is held a zither or similar musical instrument B, having strings B' stretched over a resonating-board B², preferably disposed vertically on the front of the support A, as plainly shown in the drawings. The strings B' are adapted to be picked by a picking device provided with a picker bar or frame C', extending transversely of the strings B', and on the top of the said picker-bar C' are fulcrumed at C² horizontally-disposed pickers C³, one for

each string B', the said pickers standing approximately at right angles to the strings B'.

Each picker C³ is provided at its free end 50 with an angular arm or lug C⁴, adapted to engage the string, at the rear side thereof, to pick the string on swinging the picker-bar C' forwardly, as hereinafter more fully described. Each picker C³ is pressed by a spring 55 C⁵ against a stop C⁶, preferably made of felt and secured to the top of the picker-bar C', as plainly shown in Fig. 4, so that the lug C⁴ of the picker-bar normally stands out of transverse alinement with its string B' to allow the 60 said lug C⁴ to pass between adjacent strings from the front of the same to the rear thereof, as will be readily understood by a comparison of Figs. 1 and 2. When the picker-bar C' is swung rearwardly, then the desired picker C³ 65 receives a swinging motion from the right to the left to bring its lug C⁴ in alinement with its string, so that on the next forward swinging motion of the picker-bar C' the string is sounded by the lug C⁴. In order to impart this 70 swinging motion to a picker C³ at the time the latter is in a rearmost position, as shown in Fig. 1, a bell-crank lever D is provided for each picker, the bell-crank lever being fulcrumed on the picker-bar C', and its upper member en- 75 gages the right-hand side of the picker between the fulcrum C² thereof and the stop C⁶, as shown in Figs. 1 and 2. The other member of each picker D is pivotally connected by a link D' with a movable part of the self-playing instrument—such, for instance, as the movable part of a pneumatic—connected with an action wind-chest, so that when this pneumatic is collapsed then a swinging motion is given by the corresponding link D' to the picker-lever D to 85 impart a swinging motion to the picker C³ for swinging the lug C⁴ in alinement with the string to insure subsequent sounding thereof on the forward or outward swinging motion of the picker-bar C'. 90

A swinging motion in a horizontal plane—that is, transverse to the strings B'—is given to the picker-bar C', and for this purpose the ends of the picker-bar C' are mounted on the

2
 crank-pins F of crank-disks F', secured on rock-shafts F², disposed vertically and journaled in suitable bearings A', carried on the main stand A. The crank-disks F' are provided with wrist-pins F³, pivotally connected by links F⁴ with movable parts of the self-playing instrument—for instance, with the movable parts of pneumatics F⁵, adapted to alternately collapse and open, so as to impart a rocking motion to the said crank-shafts F² for the crank-disks F' and crank-pins F to impart the desired swinging motion to the picker-bar C'. In order to insure a uniform motion of the rock-shafts F², the latter are provided with pulleys F⁶, (see Fig. 3,) connected with each other by a band F⁷, so that the rocking motion given to one shaft by its pneumatic F⁵ to the link F⁴ is transmitted to the other rock-shaft in case the latter's pneumatic does not act properly. In order to hold the connected rock-shafts in either of their two end positions, a link F⁸ is provided, pivotally connected with one of the pulleys F⁶ and with the free end of a spring F⁹, attached to a bracket on the stand A.

In the self-playing zither, which forms the subject-matter of the original application above referred to, the note-sheet is caused to travel by the action of a suitable motor over a tracker-board connected with a wind-chest, which in turn is connected with the pneumatics F⁵ and with the pneumatics for operating the levers D'. The air in the wind-chest is exhausted by suitable bellows driven by the motor above referred to. As no special claim is made in this application for the mechanism just described, it is not deemed necessary to further describe and illustrate the same, especially as other suitable means may be employed to actuate the picker-bar C' and the levers D in unison and at the proper time.

When an aperture of the note-sheet uncovers an opening in the tracker-board, then the corresponding lever D is caused to swing to actuate its picker C³ for the latter to pick its string, and when the note-sheet again covers the tracker-board opening then the lever D is returned to its former position to allow the spring C⁵ to return the picker C³ to its inactive position against the stop C⁶. The picker bar or frame C' is continually rocked as long as the note-apertures pass over the tracker-board. It is, however, understood that the pickers C³ are actuated in unison with the swinging motion given to the picker-bar C' for the pickers C³ to pick the strings at the proper time. When a note-sheet aperture registers with a tracker-board opening, a full swinging motion is given to the picker bar or frame C', and this motion is controlled by apertures in the note-sheet, as more fully described in the application above referred to.

In order to insure a proper picking of the heavy or bass strings having a core B⁴ and wire covering B⁵, (see Fig. 5,) a portion of the said covering B⁵ is removed for the lug C⁴ of a corresponding picker to engage the bare core when picking the string.

Having thus described our invention, we claim as new and desire to secure by Letters Patent—

1. A stringed musical instrument provided with a picking-frame mounted to swing over the strings, pickers fulcrumed on the said frame and having their free ends provided with angular arms for engaging the strings, and levers fulcrumed on the frame, for imparting a swinging motion to the said pickers.

2. A stringed musical instrument provided with a picking-frame mounted to swing over the strings, pickers fulcrumed on the said frame and having their free ends provided with angular arms for engaging the strings, levers fulcrumed on the frame, for imparting a swinging motion to the said pickers, and stops on the said frame, for limiting the return movement of the pickers.

3. A stringed musical instrument provided with a picking-frame mounted to swing over the strings, pickers fulcrumed on the said frame and having their free ends provided with angular arms for engaging the strings, levers fulcrumed on the frame, for imparting a swinging motion to the said pickers, stops on the said frame, for limiting the return movement of the pickers, and springs for normally holding the said pickers against the said stops.

4. A stringed musical instrument provided with a picking-frame mounted to swing toward and from the strings, pickers fulcrumed on the said frame and having their free ends provided with angular arms for engaging the strings, the said pickers standing approximately at right angles to the said strings, and levers fulcrumed on the frame, for imparting a swinging motion to the said pickers.

5. A stringed musical instrument provided with a picking-frame mounted to swing over the strings, pickers fulcrumed on the said frame and having their free ends provided with angular arms for engaging the strings, levers fulcrumed on the frame, for imparting a swinging motion to the said pickers, rock-shafts having crank-pins on which the said frame is mounted, and means for rocking the said shafts.

6. A stringed musical instrument provided with a picking-frame mounted to swing over the strings, pickers fulcrumed on the said frame and having their free ends provided with angular arms for engaging the strings, levers fulcrumed on the said frame, for imparting a swinging motion to the said pickers, rock-shafts connected with each other, to rock

- in unison, crank-pins on the rock-shafts and on which the frame is mounted, and means for imparting a rocking motion to the said rock-shafts.
- 5 7. A stringed musical instrument provided with a picking-frame mounted to swing over the strings, pickers fulcrumed on the said frame and having their free ends provided with angular arms for engaging the strings, levers fulcrumed on the said frame, for imparting a swinging motion to the said pickers, rock-shafts connected with each other, to rock in unison, crank-pins on the rock-shafts and on which the frame is mounted, means for 10 imparting a rocking motion to the said rock-shafts, means for connecting the said rock-shafts with each other, to rock the same in unison, and a spring-pressed link connected with the said means.
- 15 8. A musical instrument having a string 20 consisting of a core-string and a covering, portions of the covering being removed to leave a portion of the core bare between the ends of the string.
9. A musical instrument having a string 25 consisting of a core-string and a covering, portions of the covering being removed to leave a portion of the core bare between the ends of the string, and a picker for engaging the core at the bare portion. 30

In testimony whereof we have signed our names to this specification in the presence of two subscribing witnesses.
